UNITED STATES PATENT OFFICE.

FRANCIS WASHBURN PARSONS, OF OSTERVILLE, MASSACHUSETTS.

RAILWAY.

No. 839,633.

Specification of Letters Patent.

Patented Dec. 25, 1906.

Application filed January 9, 1906. Serial No. 295,224.

To all whom it may concern:

Be it known that I, FRANCIS WASHBURN PARSONS, a citizen of the United States, and a resident of Osterville, county of Barnstable, 5 and State of Massachusetts, have invented a certain new and useful Improvement in Railways, of which the following is a description.

My invention relates, first, to improvements in railways, and, second, to an improved 10 safety construction whereby the rail and truck may be coupled in such wise as to minimize the danger of the truck leaving the rails during its progressive movement.

The objects of my invention are, first, to 15 provide an economically-constructed railway with a minimum amount of grading and suitable for use in sparsely-settled neighborhoods as feeders to trunk-lines.

The second object of my invention is to 20 provide the railway and trucks passing over it with a safety device whereby danger of derailment is minimized.

The third object of my invention is to combine a truck carrying safety devices with a 25 railway comprising laterally-flanged safety-rails and ordinary or non-laterally-flanged rails, so that the truck at desired points may have its safety devices out of engagement with the rails.

30 I attain these objects by the mechanism illustrated in the drawings, in which—

Figure 1 is a top plan view of my new railway, showing parallel lines of rails mounted on tie-plates that are on the tops of vertical 35 posts and also showing in each line of rails laterally-flanged safety-rails and non-laterally-flanged or ordinary rails and also showing braces for the vertical rail-supporting posts. Fig. 2 is in part an enlarged trans- 40 verse section on line 2 2 of Fig. 1 and in part an end elevation of a truck provided with a safety device adapted to coöperate with the lateral safety-flanges of the rails. Fig. 3 is an enlarged view, partly in cross-section, at 45 line 3 3 of Fig. 1 and shows also in end elevation the truck referred to resting on the non-laterally-flanged or plain rails mentioned. Fig. 4 shows one form of tie-plate in perspective and detached. Fig. 5 shows in per- 50 spective a bolt-plate employed for fastening the tie-plates, and Fig. 6 shows another form of the tie-plate.

Similar numerals refer to similar parts throughout the several views.

55 The parallel safety-rails 1 1 have between

their tops and their bases 2 a lateral lengthwise-extending rib 3. This is a typical form of rail heretofore used commonly, so far as I am advised, in railway construction, the prior function of the flange 3 having been to rest 60 on filling or ballast placed under it and extending between the rails. I now use this typical form of rail in the main parts of my new railway, utilizing for the first time the laterally-projecting flange 3 as a safety web 65 or flange for coöperating with a safety device carried by the truck, as hereinafter set forth. The said form of rail forms a safety-rail in my new construction and is used preferably throughout my new railway, except at 70 points, such as terminals or switches, where it is desired to have the truck free from coupled relation with the rails. At such points I use the ordinary non-laterally-flanged rail 4. If it is not desired to have the truck coupled or 75 interlocked with the rails of the railway, the ordinary non-laterally-flanged rails 4 may be used throughout the entire length of the line without departure from my invention more broadly considered. 80

In constructing my improved railway, without reference to the particular contour of rails used and in such wise as to largely eliminate all grading, so as to simplify and economize the construction of the railway and 85 road-bed, I set posts 10 in the ground with their tops at any suitable distance thereabove and in parallel lines to support the parallel rails. The tops of the posts are of course in a horizontal plane approximately. On the 90 top of each post I fix a tie-plate 11, having an upwardly and inwardly inclined side web 12, which is preferably on the outer side of the tie-plate and overlaps the flange 2 of the rail. The plate 11 preferably has parallel down- 95 wardly-extending arms 13, that respectively engage the inner and outer sides of the posts. The horizontal part of the post-plate 11 is preferably provided with two spike or bolt holes, through one of which a spike 14 is 100 driven into the top of the post before the rail is put in place. Preferably before this spike is driven the transverse bolt-plate 15, having two spike-holes corresponding with the holes in the post-plate, is passed through opposite 105 holes or slots 16 in the downwardly-extending arms 13 of the post-plate, the spike-holes in the two plates being caused to register by the head 17 engaging one of arms 13, thus 110 forming a positioning-stop. When spike 14

is driven through its hole in the post-plate and into the top of the post, it passes through the opposed spike-hole in the bolt-plate 15, and thereby holds the same firmly in place. 5 Preferably the transverse bolt 18 is passed through opposite holes in the arms 13 13 and a hole through the intermediate portion of the post, this bolt being held by its head and a nut, as usual. The post of course is trans- 10 versely bored to form holes to receive the bolt-plate 15 and bolt 18, the holes in the arms 13 through which the bolt 18 passes being indicated by 19 and the holes in said arms through which the bolt-plate 15 passes being indicated by 16. After the plates 11 are 15 fixed on the proper number of posts any suitable form of rail having a flanged bottom is placed on the upper surfaces of the post or tie-plates with one bottom flange of the rail 20 under the upwardly and inturned flange 12 of the post-plate 11. The opposite flange of the rail is formed with a spike-hole, which is coincident with the spike-hole 20 in the bolt-plate 15 and with the spike-hole 21 in the 25 horizontal part of the post or tie-plate 11. The other spike-hole in the bolt-plate is indicated by 22, and the corresponding hole in post or tie-plate 11, through which the spike 14 passes, is indicated by 23. A spike 25 is now 30 passed through the hole in the base of the rail, through hole 21 in the post-plate, and driven downwardly into the top portion of the post and through the opposed spike-hole 20 in the transverse bolt-plate 15. The tie-plates 11 35 are thus strongly fixed in place on the posts. Preferably the flanges 12 of the tie-plates engage the outer flanges of the rails, so as to resist any lateral thrust of the trucks running on the rails. Any suitable inclined braces 40 24 may be used, if necessary or desired, for better holding the top portion of the posts in vertical position, and it is frequently desirable to connect the posts of one line with the posts of the other line by transverse tie-rods 45 25. If desired, the posts of each line may be connected at or near their upper portions by tie-rods 26, extending approximately in the direction of the length of the rails supported on one and the same line of posts 10. A rail- 50 way thus constructed is suitable for self-propelled vehicles and for other types of cars and by reason of its economic construction is particularly adapted for use as feeders to trunk-lines through sections of country 55 where there is too small a population to support a steam or electric railway of ordinary construction. The new railway is also well adapted for use in lumbering and mining countries, as well as for use in the construction 60 of railways for temporary military purposes.

The tops of the posts 10 may be at any desired height above the ground and vary with the contour thereof. The posts should be 65 set firmly in the ground, and their embedded

portions may be directly in the earth or in concrete or like bodies 27, suitably placed in the earth around the embedded portions of the posts. Generally speaking, I prefer to have the tops of the posts, and therefore the rails, 70 at a sufficient height above the ground to prevent persons and cattle from getting onto the tracks. In very many localities no grading at all will be required, the ground being cleared of trees and bushes and the rails being from, say, three to four feet above the ground or to a greater height, according to the contour of the country through which the railway is to be built. 75

In the form shown in Fig. 6 the post or tie-plate is made right angular in cross-section, the plate being generally indicated by 28 and having the depending arm 29 and the horizontal portion of said plate having the inturned holding-flange 30 and a short depending flange 31 at the end of the horizontal portion opposite the arm 29. The latter arm is provided with the aperture 32, through which a bolt-plate similar to 15 may be passed or through which a bolt similar to 18 85 may be passed. In the horizontal portion spike-holes 33 are provided for receiving spikes, such as 14 and 25, respectively. Obviously this sort of post or tie-plate is specially adapted for light railway construction, but 90 affords ample strength for heavy construction. 95

The axle of a truck (indicated by 40) is provided with the usual flanged wheels 41 41 and carries near each of its opposite ends a 100 downwardly-projecting arm 42, having a lateral extension 43, which is preferably provided with a roller 44, this roller being beneath the under surface of the laterally-projecting flange 3 of the rail and in approximate 105 contact therewith. It is apparent by this construction that any force tending to derail the truck will be resisted by the engagement of a roller 44 or arm 43 with the web 3 of the rail. I deem this construction quite desirable, especially where self-propelled vehicles of the automobile type are to be run over the railway. At the same time this safety device may be dispensed with, if desired. 110

When the railway comprises rails having 115 the lateral safety-flange 3, it is desired that the terminal rails and the rails of switches or the like should not have any such lateral or interlocking web, so that the truck may be out of interlocking engagement with the rails. 120 This form of rail is shown at 4, Figs. 1 and 3.

What I claim, and desire to secure by Letters Patent, is—

In combination with the supports for traction-rails, a tie-plate carried by each support 125 comprising a horizontal and a vertical portion, and means for securing the tie-plates to the supports including a bolt-plate passed through the vertical portion and through the post and a bolt passed through said vertical 130

portion and through the post below said bolt-plate, the bolt-plate and the horizontal portion of the tie-plate being provided with corresponding apertures through which spikes 5 may be driven to hold the plate to the post and the rail to the said tie-plate.

In testimony whereof I have hereunto

signed my name to this specification in the presence of two subscribing witnesses.

FRANCIS WASHBURN PARSONS.
